(57) **CLAIM**

The ornamental design for a work lamp, as shown and described.

DESCRIPTION

FIG. 1 is a perspective view of a work lamp showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is a perspective view thereof with the bendable portion slightly straightened and the hook rotated out.

The dashed broken lines show unclaimed portions of the article and form no part of the claimed design. The dot-dash broken lines in FIG. 3 represent the boundary of the claimed design, and form no part thereof.

1 Claim, 8 Drawing Sheets
